PICKUP TRUCK LINER

Irvin V. Hefner, 1429 Huron St.,
Metarie, La. 70005

Filed Oct. 29, 1973, Ser. No. 410,460

Term of patent 14 years

Int. Cl. D12—16

U.S. Cl. D12—156

FIG. 1.

FIG. 2.

FIG. 3.

FIG. 4.

FIG. 1 is a perspective view of a pickup truck liner showing my new design;

FIG. 2 is a top plan view thereof;

FIG. 3 is a front elevational view thereof; and

FIG. 4 is a sectional view thereof taken along line 4—4 of FIG. 1.

The side opposite to that shown in FIG. 1 is a mirror image thereof, and the rear is substantially flat and unornamented.

I claim:

The ornamental design for a pickup truck liner, substantially as shown and described.
